UNITED STATES PATENT OFFICE

HUGO LIEBETRUTH, OF NUERMBERG, GERMANY, ASSIGNOR TO THE FIRM A. LIEBETRUTH & CO. G. M. B. H., OF NUERMBERG, GERMANY

SHEET-METAL PAINT BOX

Application filed February 12, 1930, Serial No. 427,851, and in Germany October 14, 1929.

The object of this invention is to provide a sheet metal paint box, which is more particularly intended for the use of children, and which protects the paints against dropping out and rattling, is cheap to manufacture, and yet looks superior. For this purpose the invention consists essentially in the fact that the lower box member is composed of a colour-holding plate, which, by means of 5 stops, prevents the paints from jumping up, enclosing strips bent down from the lid preventing the colours from slipping about, and of a flat bottom sheet, which clamps the paints against their stops. The clamping of this 10 sheet against the under surfaces of the paints, in the case of small boxes, may be effected merely by means of supports bent out of the marginal flanges of the colour-holding plate either inwards or inwards and upwards. 15 In the case of larger paint boxes, it may be effected by means of hooks attached to certain enclosing strips, these hooks passing through slots in the bottom plate and being bent round underneath the latter.

20 Further improvements provide a hinge for the lid and a brush-holding device of hitherto unattained cheapness.

A rather large sheet metal paint box embodying all these improvements is illustrated 25 by way of example in the accompanying drawings, in which

Figure 1 is a plan of the open box,
Figure 2 a longitudinal section on the line

II—II in Figure 1, and

Figure 3 a cross section on the line
III—III in Figure 1.

The formation of the distinctive lid hinge is illustrated in Figures 4 to 9.

The paint-holding plate consists of a covering *a* with stops or abutments *d* and *f* engaging over the paints *b* and *c*, and with colour-enclosing strips *g* and *h* bent over, and also of marginal strips *i*, *i'* and *k*, which surround a flat bottom sheet *l*, and press the same with inwardly and upwardly bent supporting strips *m* against the paints from below. The sheet *l* in its turn presses the paints against the stops *d* and *f* which overlap them and holds them between the enclosing strips 50 *g* and *h*. The paints thus embedded are

therefore unable to shift either vertically or horizontally. The paints therefore cannot drop out when the box is carried in a satchel which is liable to be shaken, as has hitherto been the case with other boxes. The bottom plate *l* makes the hitherto usual sheet metal support, the projecting margins of which embraced those of a colour-holding network which was entirely open at the top, quite unnecessary; and the new bottom sheet, even 55 when made of sheet metal, is already cheaper than such a sheet metal support, on account of the saving of the projecting margins. The bottom sheet is much cheaper still when manufactured of pasteboard, cardboard or 60 other material, which is considerably cheaper than sheet metal. The pasteboard or cardboard may be impregnated or varnished to 65 make it waterproof.

In order that even rather large bottom 70 sheets may not sag in the middle, suitably arranged framing strips *g* are prolonged into hooks *n* and *o*, which pass through slots *p* in the bottom sheet and engage under the said bottom sheet with claws *o*. For rectangular paints the stops *d* are advisable, which overlap the paints, for the paints look nice with bevelled corners, and the paint brush is worn away less by the corner stops when taking up the colour. Projecting cover claws *f* 75 for rectangular paints *b* and for round paints *c* may however also be employed at any positions above the paints.

For holding the paint brush *q*, *r* a channel *s* is pressed downwards in the cover *a*. To the latter is attached a tunnel-like channel *t* pressed upwards, under which the brush handle *q* is inserted. When the box is tilted the brush is held by the groove and tunnel *t*.

The cover *a* ascends with oblique marginal strips *u* to the top *v* of the rim strips *k* and *i*, on the one hand in order that the latter may be as obvious as possible and, on the other hand, in order to provide room under the closed lid *w* for tubes *x*, which likewise rest 85 upon the bottom sheet *l* in cut out places *y* in the cover *a*, bounded by marginal ledges *g'*, and are slid under holding claws *z* bent up between the marginal ledges *g'*.

For the production of pivots for the lid 100

hinge, parallel slots 3 are stamped out of the rear rim *i*', leaving bridge pieces 4 (Figure 4) between them. These bridge pieces are then joggled backwards over the rim, as shown in Figure 5, and bent together by means of special pliers into tubular elements 4' open in the front (Figures 6 and 7), round which are bent the usual open eyes 5 attached to the lid *w*, as shown in Figures 8 and 9.

10 This hinge construction is particularly cheap, because it renders unnecessary the wire hinge pins that have hitherto been considered indispensable.

The paints are put in while the sheet supports *m* are still in the same plane as the marginal rims *i* and *k*, and the hooks *n*, *o* are still straight tongues. To insert the paints, the paint-holding plate *a* is turned over with the top *v* of its rim on the table. When the paints have been put in from above, the sheet *l* is mounted with its slots *p* upon the tongues that are subsequently to form the hooks *n*, *o*, and their ends are then bent over to form gripping claws *o*. Finally the supporting ledges *m* are bent mechanically. In place of the continuous supporting ledges *m*, shorter supporting feet may be employed.

What I claim is:

1. A sheet metal paint box, more particularly for children, comprising a paint-holding plate formed with apertures through which the paints contained in the box appear, abutments on the paint-holding plate extending over the apertures to prevent the paints jumping up through the apertures, framing strips bent down from the edges of the said apertures to enclose the paints at the sides and prevent them from slipping in any direction parallel to the paint-holding plate, marginal rims extending downwards from the outer edges of the paint-holding plate, and a flat bottom sheet fitting within the said marginal rims and adapted to be held by them against the under sides of the paints and to keep the paints pressed up against the abutments on the paint-holding plate.

2. A sheet metal paint box, more particularly for children, comprising a paint-holding plate formed with substantially rectangular apertures through which rectangular paints contained in the box appear, abutments on the paint-holding plate extending over the corners of the apertures to prevent the paints jumping up through the apertures, framing strips bent down from the edges of the said apertures to enclose the paints at the sides and prevent them from slipping in any direction parallel to the paint-holding plate, marginal rims extending downwards from the outer edges of the paint-holding plate, and a flat bottom sheet fitting within the said marginal rims and adapted to be held by them against the under sides of the paints and to keep the paints

pressed up against the abutments on the paint-holding plate.

3. A sheet metal paint box, more particularly for children, comprising a paint-holding plate formed with apertures through which the paints contained in the box appear, abutments on the paint-holding plate extending over the apertures to prevent the paints jumping up through the apertures, framing strips bent down from the edges of the said apertures to enclose the paints at the sides and prevent them from slipping in any direction parallel to the paint-holding plate, marginal rims extending downwards from the outer edges of the paint-holding plate, a flat bottom sheet made of cheap material such as pasteboard, cardboard and the like, fitting within the said marginal rims and adapted to be held by them against the under sides of the paints and to keep the paints pressed up against the abutments on the paint-holding plate.

4. A sheet metal paint box, more particularly for children, comprising a paint-holding plate formed with apertures through which the paints contained in the box appear, abutments on the paint-holding plate extending over the apertures to prevent the paints jumping up through the apertures, framing strips bent down from the edges of the said apertures to enclose the paints at the sides and prevent them from slipping in any direction parallel to the paint-holding plate, marginal rims extending downwards from the outer edges of the paint-holding plate, a flat bottom sheet made of cheap material such as pasteboard, cardboard and the like, fitting within the said marginal rims and adapted to be held by them against the under sides of the paints and to keep the paints pressed up against the abutments on the paint-holding plate.

5. A sheet metal paint box, more particularly for children, comprising a paint-holding plate formed with apertures through which the paints contained in the box appear, abutments on the paint-holding plate extending over the apertures to prevent the paints jumping up through the apertures, framing strips bent down from the edges of the said apertures to enclose the paints at the sides and prevent them from slipping in any direction parallel to the paint-holding plate, marginal rims extending downwards from the outer edges of the paint-holding plate, and a flat bottom sheet fitting within the said marginal rims, the lower edges of the marginal rims being bent inwards and upwards after the insertion of the flat bottom sheet so as to hold the said flat bottom sheet against the under sides of the paints and to keep the paints pressed up

against the abutments on the paint-holding plate.

6. A sheet metal paint box, more particularly for children, comprising a paint-holding plate formed with apertures through which the paints contained in the box appear, abutments on the paint-holding plate extending over the apertures to prevent the paints jumping up through the apertures, framing strips bent down from the edges of the said apertures to enclose the paints at the sides and prevent them from slipping in any direction parallel to the paint-holding plate, marginal rims extending downwards from the outer edges of the paint-holding plate, a flat bottom sheet fitting within the said marginal rims and adapted to be held by them against the under sides of the paints and to keep the paints pressed up against the abutments on the paint-holding plate, tubular hinge pins 70 pressed integrally out of the paint-holding plate, a lid, and eyelets on the lid adapted to engage with the tubular hinge pins to form hinges.

7. A sheet metal paint box, more particularly for children, comprising a paint-holding plate formed with apertures through which the paints contained in the box appear, abutments on the paint-holding plate extending over the apertures to prevent the paints jumping up through the apertures, framing strips bent down from the edges of the said apertures to enclose the paints at the sides and prevent them from slipping in any direction parallel to the paint-holding plate, the said flat bottom sheet being formed with small slots, and downward extensions of some of the framing strips, the said downward extensions passing through the slots in the flat bottom sheet and being bent over on the under side thereof to support the bottom sheet against sagging.

8. A sheet metal paint box, more particularly for children, comprising a paint-holding plate formed with apertures through which the paints contained in the box appear, abutments on the paint-holding plate extending over the apertures to prevent the paints jumping up through the apertures, framing strips bent down from the edges of the said apertures to enclose the paints at the sides and prevent them from slipping in any direction parallel to the paint-holding plate, marginal rims extending downwards from the outer edges of the paint-holding plate, and a flat bottom sheet fitting within the said marginal rims and adapted to be held by them against the under sides of the paints and to 80 keep the paints pressed up against the abutments on the paint-holding plate, the paint-holding plate being formed with a depressed groove adapted to hold the greater part of a paint brush and with a shorter pressed-up 85 groove in alignment therewith adapted to over-arch the brush and prevent it from jumping out of its place.

9. A sheet metal paint box, more particularly for children, comprising a paint-holding plate formed with substantially rectangular apertures through which rectangular paints contained in the box appear, abutments on the paint-holding plate extending over the corners of the apertures to prevent the paints jumping up through the apertures, framing strips bent down from the edges of the said apertures to enclose the paints at the sides and prevent them from slipping in any direction parallel to the paint-holding plate, the 105 paint-holding plate being formed with a depressed groove adapted to hold the greater part of a paint brush and with a shorter pressed-up groove in alignment therewith 110 adapted to over-arch the brush and prevent it from jumping out of its place, a marginal strip surrounding the paint-holding plate and inclined upwards from the level of the surface containing the paint apertures, marginal rims extending downwards from the 115 outer edges of the inclined marginal strip, a flat bottom sheet made of cheap material such as pasteboard, cardboard and the like, water-proofed by such means as impregnation, varnishing and the like, fitting within the said 120

apertures to enclose the paints at the sides and prevent them from slipping in any direction parallel to the paint-holding plate, marginal rims extending downwards from the outer edges of the paint-holding plate, a flat bottom sheet fitting within the said marginal rims and adapted to be held by them against the under sides of the paints and to keep the paints pressed up against the abutments on the paint-holding plate, tubular hinge pins 75 pressed integrally out of the paint-holding plate, a lid, and eyelets on the lid adapted to engage with the tubular hinge pins to form hinges.

10. A sheet metal paint box, more particularly for children, comprising a paint-holding plate formed with apertures through which the paints contained in the box appear, abutments on the paint-holding plate extending over the apertures to prevent the paints jumping up through the apertures, framing strips bent down from the edges of the said apertures to enclose the paints at the sides and prevent them from slipping in any direction parallel to the paint-holding plate, marginal rims extending downwards from the outer edges of the paint-holding plate, and a flat bottom sheet fitting within the said marginal rims and adapted to be held by them against the under sides of the paints and to 90 keep the paints pressed up against the abutments on the paint-holding plate, the paint-holding plate being formed with a depressed groove adapted to hold the greater part of a paint brush and with a shorter pressed-up 95 groove in alignment therewith adapted to over-arch the brush and prevent it from jumping out of its place.

11. A sheet metal paint box, more particularly for children, comprising a paint-holding plate formed with substantially rectangular apertures through which rectangular paints contained in the box appear, abutments on the paint-holding plate extending over the corners of the apertures to prevent the paints jumping up through the apertures, framing strips bent down from the edges of the said apertures to enclose the paints at the sides and prevent them from slipping in any direction parallel to the paint-holding plate, the 105 paint-holding plate being formed with a depressed groove adapted to hold the greater part of a paint brush and with a shorter pressed-up groove in alignment therewith 110 adapted to over-arch the brush and prevent it from jumping out of its place, a marginal strip surrounding the paint-holding plate and inclined upwards from the level of the surface containing the paint apertures, marginal rims extending downwards from the 115 outer edges of the inclined marginal strip, a flat bottom sheet made of cheap material such as pasteboard, cardboard and the like, water-proofed by such means as impregnation, varnishing and the like, fitting within the said 120

marginal rims the lower edges of the marginal rims being bent inwards and upwards after the insertion of the flat bottom sheet so as to hold the said flat bottom sheet against the undersides of the paints and to keep the paints pressed up against the abutments on the paint-holding plate, the said flat bottom sheet being formed with small slots, downward extensions of some of the framing strips, the said downward extensions passing through the slots in the flat bottom sheet and being bent over on the under side thereof to support the bottom sheet against sagging, tubular hinge pins pressed integrally out of the paint-holding plate, a lid, and eyelets on the lid adapted to engage with the tubular hinge pins to form hinges.

In testimony whereof I have signed my name to this specification.
